PLLC; Brittany Haanan

(57) **CLAIM**

The ornamental design for a blade holder, as shown and described.

DESCRIPTION

FIG. 1 is a front view of a blade holder showing our new design, illustrated in combination with an unclaimed blade and a knife handle;

FIG. 2 is a front view of the blade holder of FIG. 1.

FIG. 3 is a front perspective view of the blade holder of FIG. 1.

FIG. 4 is a top perspective view of the blade holder of FIG. 1.

FIG. 5 is a top view of the blade holder of FIG. 1.

FIG. 6 is a rear view of the blade holder of FIG. 1, illustrated in combination with the blade and the knife handle of FIG. 1.

FIG. 7 is a rear view of the blade holder of FIG. 1.

FIG. 8 is a rear perspective view of the blade holder of FIG. 1.

FIG. 9 is a bottom perspective view of the blade holder of FIG. 1.

FIG. 10 is a bottom view of the blade holder of FIG. 1.

FIG. 11 is a left side view of the blade holder of FIG. 1.

FIG. 12 is a front view of the blade holder of FIG. 1 in combination with a blade and a handle.

FIG. 13 is a rear view of the blade holder of FIG. 1 in combination with the blade and the handle of FIG. 12.

FIG. 14 is a front view of the blade holder of FIG. 1 in combination with a blade and a handle; and,

FIG. 15 is a rear view of the blade holder of FIG. 1 in combination with the blade and the handle of FIG. 14.

The broken line portion of the blade holder form no part of the claimed design. The broken line showings of the blade and knife handle are provided for purposes of environment and form no part of the claimed design.

1 Claim, 13 Drawing Sheets
